(57) **CLAIM**

I claim the ornamental design for the soap object, as shown and described.

DESCRIPTION

FIG. 1 is a perspective view of a soap object showing our new design according to a first exemplary embodiment;

FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and
FIG. 7 is a bottom plan elevational view thereof;
FIG. 8 is a perspective view of a soap object showing our new design according to a second exemplary embodiment which includes a hologram shown in phantom;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof; and
FIG. 14 is a bottom plan elevational view thereof.
FIG. 15 is a perspective view of a soap object showing our new design according to a third exemplary embodiment;
FIG. 16 is a front elevational view thereof;
FIG. 17 is a rear elevational view thereof;
FIG. 18 is a right side elevational view thereof;
FIG. 19 is a left side elevational view thereof;
FIG. 20 is a top plan view thereof; and
FIG. 21 is a bottom plan elevational view thereof;
FIG. 22 is a perspective view of a soap object showing our new design according to a fourth exemplary embodiment which includes a hologram shown in phantom;
FIG. 23 is a front elevational view thereof;
FIG. 24 is a rear elevational view thereof;
FIG. 25 is a right side elevational view thereof;
FIG. 26 is a left side elevational view thereof;
FIG. 27 is a top plan view thereof; and,
FIG. 28 is a bottom plan elevational view thereof.
The broken lines are shown for illustrative purposes only and form no part of the claimed design.
